ROCKER ARM FOR OVERHEAD VALVES

This invention relates to a valve control for a rocker arm in an overhead valve internal combustion engine in which the overhead camshaft lies parallel to the rows of valve stems. This invention is particularly useful for a high-speed air-cooled high-capacity fuel injection engine.

The valve rocker arms in conventional engines directly engage both the cam on the camshaft and the valve stem. These rocker arms for the valves are, in this case, very short for structural reasons so that the rocker arms describe small arcs during their movement. Consequently, if the axis of the rocker arm lies parallel to the camshaft axis, a thrust is produced which acts transversely on the valve stem and which leads to a premature wear and tear on the slide bearing guiding the valve stem as well as premature wear and tear on the valve itself. If, however, the axis of the rocker arm is arranged at a right angle to the valve stem axis, then this produces very unfavorable movement conditions on the other end of the rocker arm on the cam.

The object of this invention is to produce a simple manner to eliminate the aforesaid disadvantages and also to produce a valve control which permits adequate cylinder head cooling and which permits the positioning of the fuel injection nozzle and, if need be, an additional spark plug in such a way that the flow of cooling air is insignificantly disturbed and also that the fuel injection nozzle, as well as the spark plug, if used, are easily accessible for maintenance purposes.

In general, these objects of the invention are obtained by combining the following features:

- One rocker arm is positioned on a tubular center portion of the other rocker arm and with the axis of the center portion extending at a right angle to the camshaft axis.
- Each rocker arm has one end engaged with the cam by means of a cam follower which is flattened on its cam side.
- The other end of the rocker arm engages the valve stem through a flat side on a ball which is movably mounted in a plug in the rocker arm.

This construction produces operating conditions and wear-and-tear conditions as exist in mushroom tappets. The cam follower which has one side flattened and bears on the cam has a linear contact identical with that of a mushroom tappet and this is maintained by the movability of the cam follower in every rocker arm position. The result is very little wear and tear on the cams and the contact surface of the rocker arm and also makes possible the use of a spherical cam. Because of the flattened ball on the other end of the rocker arm, there is also produced between the valve stem and rocker arm, and in every position of the rocker arm, a satisfactory surface contact which also has very good lubricating conditions, that is, it always carries a sizable film of lubricating oil so that the component forces exerted on the valve stem are especially small. The life span of the valve guide bearing is thus increased to a considerable extent. It is further of especial advantage in that, because of the crosswise arrangement of the rocker arms, it is possible to make the arms longer. This lengthening of the arms permits them to swing in larger arcs which greatly reduces the component forces on the valve stem. Finally, this construction permits the individual parts to be easily removed as well as the easy adjustment of the parts interplay. Also, the installation and removal of each valve control arrangement is very simple. The valve control can be separately removed from each cylinder without changing in any way whatsoever the valve adjustment as such.

In the prior art, insofar as feature (a) is concerned, a valve control for internal combustion engines has been used for overhead valves operated by a camshaft extending parallel to the plane of the valve stems and having rocker arms in which each single rocker arm is mounted on the tubular center portion of the other rocker arm. However, in such construction, the camshaft is positioned in the crank case and therefore is a push rod system.

The aforesaid feature (b) has been used only with a conventional rocker arm valve control.

Feature (c) has been used for a specific push rod valve control, whereas this invention provides a lubricant film between the rocker arm and the valve stem.

The above prior art features are therefore features which have been heretofore always used for other individual requirements and have not been brought together in the combination of this invention. The aforesaid substantial advantages of this invention are gained only by the combination of these features.

The means by which the objects of this invention are obtained are described more fully with reference to the accompanying drawings in which:

FIG. 1 is a top plan view of the overhead valve assembly;

FIG. 2 is a side elevational view taken on the line 2-2 of FIG. 1;

FIG. 3 is a cross-sectional view taken on the line 3-3 of FIG. 1; and

FIG. 4 is a cross-sectional view through the cam and cam follower as taken on the line 4-4 in FIG. 3.

As shown in FIGS. 1 and 2, the camshaft 1 carries cams 1a and 1b. Cam 1a actuates rocker arm 2 which is composed of two arm portions 2a and 2b. Rocker arm 2 has a third arm portion 2c mounted on the tubular center portion 3c of the other rocker arm 3 with the axis of rocker arm 3 extending at a right angle to the axis of cam shaft 1. Rocker arm 3 has arm portions 3a and 3b which are clamped on the center tubular portion 3c by means of screws 3d. Rocker arm 3 is mounted on bolt 10.

Arm portions 2a and/or 3a are each provided with a cylindrical recess or cavity 4, as shown in FIGS. 2 and 3, in which is seated a cam follower 5 having a flat side 5a. The cam follower 5 has a hollow bore 5b for purposes of saving weight. The opening center angle of cylindrical cavity 4 is less than 180°, FIG. 3, and embraces cam follower 5 to prevent the follower from falling out.

The flattened follower 5 has collars 5c, FIGS. 2 and 4, each one having a recess 5d into which securing pins 6 are positioned. The two rocker arm portions 2b and/or 3b have at their ends 2d and/or 3e cylindrical openings 2e and/or 3f. The curved ends 2d and/or 3e have slots 2f and/or 3g which are clamped together by screws 2g and/or 3h, FIG. 1. Plugs 7 with hexagonal wrench receiving sides 7a are mounted in the openings 2e and/or 3f. The lower ends of plugs 7 have similar sockets 7b for the reception of the ball spherical member 8 having a flat side 8a which engages with play the circular head 9a of the valve stem 9.

The operation of this assembly is as follows:

The followers 5 have their flat sides 5a engaging the cams 1a and/or 1b exactly in the manner of mushroom tappets. This results in a linear contact which, because of the elasticity or elastic deformation of the material, becomes a surface contact having relatively low surface pressure. This, however, is only possible since the follow 5 can turn in the cylindrical recess 4 in the rocker arm portions 2a and/or 3a. In a conventional construction without a movable cam follower, it would be necessary that the end of the rocker arm is also formed as a cam or, in other words, curved. This would theoretically produce a dotlike contact which, in practice because of the elastic deformation of the material, would lead to an infinitesimal circular contact surface which would cause an extraordinarily larger specific surface pressure with resulting

In contrast thereto, this invention creates very slight surface pressure because of the movable cam follower despite the fact that the rocker arm operates directly on the cam. The same is true for the two arm portions 2b and/or 3b which act directly on the valve stems. In this case, we have inserted a known flat-sided ball or spherical member 8 between the arm 2b and/or 3b and the valve stem 9. Thus, during the operation of the valve drive, there is no contact of the rocker arms 2b and/or 3b on the end surfaces of the valve with dangerously high surface pressure of the valve with dangerously high surface pressure because of the movement or displacement of the rocker arm. Above all, because of the short arc around which the arm

portions of the rocker arm are moving or swinging and because of the small surface pressure which results from a good film of lubricating oil, there are no strong component forces which act on the valve guide bearing and which would cause rapid wear and tear of the guide bearings in conventional constructions. The flattened sides 8a of the members 8 slide in this invention back and forth on the end surfaces of the valve stems because of the arcular movements of the rocker arms and without being subject to the dangerous component forces exerted on the guide bearings.

The flat cam followers 5, FIGS. 3 and 4, are inserted into the cylindrical recesses 4 by turning the followers 5 90°. When this is done, it is very easy to position the follower 5 into recess 4. Then when the follower 5 is turned to its original position, it is impossible for it to fall out since the opening center angle is less than 180°. Collars 5c adjacent the ends of followers 5 prevent the followers from sliding out in an axial direction while safety pins 6 positioned in the recesses 5d of the collars 5c prevent the followers from turning back into the position into which they were originally inserted.

The flat-sided spherical members 8 are partially enclosed and held in the plugs 7 by a slight constriction of the plug opening and are thus prevented from falling out downwardly. By means of this, it is impossible, even during valve flutter,

because of the racing of the engine and the lifting of rocker arms 2 and 3 from the cams 1a and/or 1b engaged therewith for either the cam follower 5 or the spherical member 8 to fall out or to jam.

Having now described the means by which the objects of the invention are obtained,

We claim:

1. A rocker arm valve control for an overhead multivalve internal combustion engine including cylinders comprising overhead valve stems, an overhead camshaft extending parallel to the plane of the valve stems,

a. a first rocker arm 3 having a tubelike center portion 3c having its axis at a right angle to the axis of said cam shaft, and a second rocker arm 2 for the same cylinder mounted on said center portion;

b. a cam follower 5 turnably mounted on an end 2a, 3a of each arm 2, 3 and having a flat side 5a bearing in linear contact on its respective cam; and

c. a plug 7 having a recess mounted in the other end 2b, 3b of each arm, a spherical member 8 movably positioned in said recess, and a flat side 8a on said member 8 bearing on its respective valve stem.
